UNITED STATES PATENT OFFICE

FRANK J. CURRAN, OF SAN FRANCISCO, CALIFORNIA, ASSIGNOR, BY MESNE ASSIGNMENTS, TO STEAM POWER, INC., A CORPORATION OF DELAWARE

BOILER CONSTRUCTION

Application filed July 30, 1923, Serial No. 654,751. Renewed June 14, 1932.

The present invention relates to improvements in boiler constructions and its particular object is to provide a boiler that will generate steam with an extremely high degree of efficiency. One of the main objects of the invention is to provide a boiler construction in which steam passing upwardly through the steam drum is turned downwardly into the steam drum in such manner as to develop the efficiency of the boiler advantageously. Another object of the invention as to provide a boiler construction provided with boiler tubes and means for cutting out at will individual tubes of the boiler. An object of the invention is to provide a type of boiler construction in which the various boiler tubes, water drums, steam drums and valves cooperate in a manner for efficiently producing steam. Further objects and advantages of my device will appear as the specification proceeds. The preferred form of my boiler construction is illustrated in the accompanying drawings in which Figure 1 shows a vertical section through the boiler and the fire box, Figure 2 a horizontal section taken along line II-II of Figure 1, Figure 3 a horizontal section taken along line III-III of Figure 1, Figure 4 a horizontal section taken along line IV-IV of Figure 1, Figure 5 a perspective detail view of an air inlet pipe, Figure 6 an enlarged sectional detail view of a portion of Figure 2, and Figure 7 an enlarged detail view of the upper left hand portion of Figure 1. While I have shown only the preferred form of my invention I wish it to be understood that various changes and modifications may be made within the scope of the claim hereto attached without departing from the spirit of the invention.

The fire box (1) which is preferably cylindrical in form and open on top is surrounded by a chamber (2) formed by the cylindrical housing (3), the bottom of the fire box being held in spaced relation to the bottom of the housing (3) by means of the stays (4) which are preferably made tubular to present a large heating surface per weight unit of material used. The fire box and the housing may be formed integral,

with a top member (6) closing the top of the chamber (2). A cylindrical compartment or chamber (7) surrounds the chamber (2) and its outer wall (8) which connects with the wall (3) on top as shown at (9), 55 is formed to allow air currents introduced into the outer chamber to pass around and underneath the inner chamber (2).

Referring particularly to Figure 4 it will be seen that the outer chamber communicates with a tangentially arranged inlet pipe (11) 60 through which air may be forced into the chamber (7) under pressure and caused to rapidly revolve around the inner chamber (2). A pipe or other suitable conduit (12) 65 is supported in the two cylindrical walls defining the inner chamber in a horizontal position and slanted to approach the general direction of the air currents. This pipe is shown in detail in Figure 5 and is formed with a flap (13) projected into the chamber (7) in such a manner as to catch part of the air currents revolving through that chamber and to divert them into the fire box. At its inner 70 end the pipe (12) is provided with a similar flap (14) on the opposite side so as to turn the air currents passing through the pipe into a tangential direction. It should be understood then that the air currents introduced through the pipe (12) rotate and whirl in the 75 fire box in the same manner as they rotate in the outer chamber. Fuel is introduced into the fire box in radial direction through the pipe (16) controlled by a valve (17). Before entering the fire box the fuel is atomized by 80 the atomizer (18) not shown in detail but described in a co-pending application and thereafter ignited by any suitable means as by the electrodes (19). To maintain the whirling or 85 rotating motion of the air currents I introduce several other intake pipes (21) evenly distributed peripherally and resembling in form and arrangement the pipe (12) but preferably made with somewhat smaller flaps so as to catch less air than the main pipe (12) 90 which latter is close to the intake (11).

The air whirling around the cylindrical wall (3) is permitted to enter underneath the bottom of said cylindrical wall and to be forced into the center of the fire box through 95 100

5 apertures (22) in the bottom of the second chamber and the passage (23) communicating therewith and terminating in small conduits (24) supported in a central projection (26) in the fire box. The conduits (24) are formed at their ends to guide the inrushing air downwardly as well as tangentially and preferably in a direction opposite to that of the air currents whirling through the peripheral portion of the fire box. Downward motion is imparted through the downward curve (27) illustrated in Figure 1 and tangential motion through the lateral curve illustrated at (28) in Figure 4.

10 15 This construction of the fire box offers the following advantages. The inner chamber (2) which it will be seen later is filled with water to be converted into steam cools the sides and the bottom of the fire box while 20 absorbing heat units from the same in the most direct manner and allows of the employment of continually maintained extreme heat. This extreme heat is brought about by the particular construction of the fire box and 25 the means for supplying air and fuel. The rapidly rotating and whirling air currents are charged directly after entering the fire box with atomized fuel igniting at the time of its entry into the fire box and cause a complete 30 combustion of the same even though a heavy low grade fuel be used. The central air currents whirling through the fire box in the opposite direction prevent the formation of cold spots or pockets.

35 40 The water circulating system includes a large coil (31) wound to form a cylinder of slightly larger diameter than the fire box the upper end of which is connected through the pipe (32) with any suitable supply of water. The said coil is disposed above the fire box in such a manner as to enclose a cylindrical space having substantially the same or a little larger diameter than the fire box. The coil is surrounded by a cylindrical wall (33) 45 which latter preferably forms a continuation of the cylindrical wall (3) constituting the division between the chambers (2) and (7), and a heavy wall (34) of heat-insulating material is placed around the wall (33). The 50 lower end of the coil (31) discharges into the chamber (2). A plurality of conically arranged coils (37) are placed directly above the fire box in overlying relation, with the coil terminating at its lower end in a pipe 55 (38) extending into the bottom portion of the chamber (2), the ends being preferably arranged so as to be evenly distributed throughout the chamber. The upper end of each conical coil (37) terminates in a vertical pipe (41) which latter pipes are turned sideways as shown at (42) and then upward again to 60 pass through tubular openings of the steam dome (43) as shown at (44). After reaching the top of the steam dome which latter consists of two plates (46) and (47) disposed in

spaced relation by means of the tubular spacing members (48), the pipes are turned back on themselves so as to project into the steam dome. The ends (49) of the pipes are provided with openings (51) allowing the mixture of the water and steam produced in the pipes at that time to be discharged into the steam dome. As shown in the detail view of Figure 6 the perforations (51) are arranged to give to the water and steam a tangential direction whereby the mixture is whirled around in the steam dome and separated by centrifugal force so that the water is forced outwardly and the steam inwardly. The water settles on the bottom plate of the steam dome and is allowed to return to the chamber (2) through the drain pipes (52) which latter extends slightly above the bottom plate of the steam dome as shown at (53) so as to allow a small amount of water to collect on the bottom plate before it is drained off. It should be noted that the drain pipes (52) are disposed on the outside of the coil (31) which latter coil is preferably indented for this purpose as shown at (54) in Figure 3. The coil (31) therefore serves to protect the drain pipes (52) from the extreme heat above the fire box. The drain pipes are provided near their bottom with valves (56) which allow the water to run downwardly but which prevent water from being forced upwardly. The valves are well known in the art and therefore not illustrated in detail.

56 The steam forced inwardly by centrifugal action is received through perforations by a central pipe (57) extending through the steam dome and terminating below the dome in a superheating coil (58) which latter ends into the horizontal pipe (59) leading to the outside of the boiler. The upper end of the central pipe (57) connects with the horizontal pipe (61) provided with a steam gage (62). Each of the coils (37) is provided with a lower shut-off valve (63) immediately above the chamber (2) and with an upper shut-off valve (64) above the steam dome. The latter valve is shown in detail in Figure 7. In the immediate proximity of this valve is provided a second valve (66) controlling an auxiliary outlet (67) for the vertical pipes (44) communicating with the coils (37). This arrangement allows each single coil with its pipe system to be eliminated from the whole system by closing the two valves (63) and (64) and it furthermore allows each individual coil to be blown off by closing the valve (64) and opening the valve (66) which latter should preferably be a quick acting gate valve well known in the art. A space (68) above the steam dome communicates with the chimney (69) through which the products of combustion escape.

57 The operation of the boiler may be described as follows: Cold water enters through the pipe (32) into the pre-heating

coil (31). Means are provided for maintaining the water in the said pre-heating coil at a certain level. Since these means are well known in the art and not claimed in the present invention they are not shown in the drawings. The pre-heating coil which while absorbing heat units also protects the wall (33) surrounding the same and the drain pipes (52) behind the coil delivers the heated water into the chamber (2) where the water absorbs additional heat while at the same time cooling the walls of the fire box. The tubular form of the stays (4) assists in heating the water rapidly due to its large heating surface. The water as it has become heated rises in the coils (37) where the heat is still further increased due to the fact that the coils (37) are disposed immediately above the fire box. After passing through the coils (37) the water has been turned partly into steam and it is discharged in the steam chamber through the perforations (51). These perforations are arranged to impart a tangential direction to the mixture of the steam and water which causes the two elements to separate and which forces the steam inwardly while the water settles in the steam dome and is returned through the pipes (52) into the chamber (2). The steam within the steam dome passes through the perforations (55) into the superheating coil (58) and is finally conveyed to the place where it is to be used through the pipe (59).

The products of combustion rising from the fire box are guided away through the tubular openings in the steam dome and through the chimney (69).

I claim:

In a device of the character described, a vertical casing, a fire box at the bottom of said casing, a steam drum extending across said casing in the upper part thereof and having flues passing therethrough to discharge the heating gases, a water drum and steam tubes connecting said water drum with said steam drum, said steam tubes passing upwardly through said flues and then turning downwardly into the steam drum at its periphery and discharging steam substantially tangentially of the wall of the drum, means for cutting out individual tubes from the boiler including for each tube a valve connected therewith above the steam drum and having a stem extending to the outside of said casing, and means for blowing out said tubes when cut out including pipes connected with said tubes back of said valves and extending to the outside of said casing.

FRANK J. CURRAN.
